(57) **CLAIM**

The ornamental design for a pet walking belt, as shown and described in the accompanying drawings.

DESCRIPTION

FIG. 1 is a perspective view of the pet walking belt;
FIG. 2 is a right side elevational view of the pet walking belt;
FIG. 3 is a left side elevational view of the pet walking belt;
FIG. 4 is a front side elevational view of the pet walking belt;
FIG. 5 is a rear side elevational view of the pet walking belt;
FIG. 6 is a top plan view of the pet walking belt; and,
FIG. 7 is a bottom plan view of the pet walking belt.
The features shown in broken lines in the drawings illustrate environment that forms no part of the claimed design.
